[57] CLAIM

The ornamental design for a comb, as shown and de-
scribed.

DESCRIPTION

FIG. 1 is a perspective view of a comb showing my new
design;

FIG. 2 is a top plan view thereof;

FIG. 3 is a side elevational view thereof;

FIG. 4 is a perspective view of a comb showing a sec-
ond embodiment of my new design which is a mirror
image of the first embodiment;

FIG. 5 is a side elevational view of a comb showing a
third embodiment of my new design; and

FIG. 6 is a top plan view thereof.
